UNITED STATES PATENT OFFICE.

WILLIAM H. MASON, OF LEESBURG, OHIO.

WIRE-FENCE FASTENER.

Application filed September 15, 1921. Serial No. 500,983.

To all whom it may concern:

Be it known that I, WILLIAM H. MASON, a citizen of the United States, residing at Leesburg, in the county of Highland and 5 State of Ohio, have invented a certain new and useful Improvement in Wire-Fence Fasteners, of which the following is a specification.

The fence staples now in common use 10 usually require two men to successfully secure them in place—one man to hold a heavy object at the rear of the post and another at the face of the post to do the driving.

15 The object of the present invention is to provide an improved form of staple that can be applied by one man with a pair of pliers. Fence posts for wire fences are now usually made of angle iron or T-bar and the 20 hole for the passage of the staple is sometimes quite close to the web of the bar, hence a further object of the invention is to provide a staple that can be applied with a pair of pliers notwithstanding the staple hole 25 may be close to the web and which may be applied through a hole on either side of the web. It is a further object of the invention to provide a staple in such a form that no bending is required except that needed to 30 turn a single wire around the fence wire.

The invention is embodied in the example herein shown and described.

In the accompanying drawings—

35 Figure 1 is a front view of a fraction of post and fence wire showing my staple applied but before the same has been bent to grip the fence wire.

Fig. 2 is an edge view of the same.

40 Fig. 3 is a view like Fig. 1 showing the free end of the staple bent around the fence wire to grip the same.

Fig. 4 is an end view of the same.

Fig. 5 is a rear view of the invention as seen in Fig. 3.

45 Fig. 6 is a view like Fig. 5 showing two staples as applied to a T-bar fence post.

Fig. 7 is a perspective view of the invention.

50 My invention is useful more particularly in connection with a post provided with a hole 11 across which the fence wire 12 is extended against a flat face of the post.

The staple, as shown, is made of a piece of wire bent to form a loop 10 to lie in the

hole 11 of the fence post in a plane at right angles thereto and embrace the fence wire 12, a leg portion 13 extending from one of the loop legs and at right angles to the loop and a further extension 14 bent to stand at right angles to the leg portion 13, and a short leg 15 extending from the other loop leg in the same direction as the leg portion 13 and parallel thereto. The extension 14 is the portion that is bent about the fence wire by the application of a pair of pliers while the short leg portion 15 and leg portion 13 serve as efficient braces against the bending effort.

The staple in its marketed form is as shown in Fig. 7. It is applied to the post and fence wire by first passing the free or long 70 end 14 through the hole in the post at one side of the wire and then the other short leg 15 is inserted through the hole over the other side of the wire so that the loop shall straddle the fence wire as shown in Figs. 1 and 75 2, after which the free end 14 is bent around the fence wire to grip the same as shown in Figs. 3, 4, 5 and 6. When the staple is provided in the form shown the only operation necessary on the part of one securing the 80 fence wire to the post is to pass the legs while embracing the fence wire and then twist the end of the long leg about the fence wire.

The forms and dimensions can be varied 85 without departing from the gist of the invention as claimed.

What I claim is:

1. As an article of manufacture, a device for fastening a wire to a post having a hole 90 therethrough crossed by the wire, said device consisting of a loop portion having two legs bent off from said loop and one of said legs further bent in the same direction as the loop and substantially parallel thereto. 95

2. In combination with a fence post having a through hole and a fence wire crossing said hole, a device for fastening said fence wire to the post consisting of a metallic strip bent to form a loop portion embracing the 100 fence wire and lying within said hole at a right angle to the plane of the portion of post having said hole and two leg portions standing off from said loop portion in the same direction and at an angle to the plane 105 of said loop portion, bent to secure the fence wire to the post.

WILLIAM H. MASON.
